United States Patent Office

Des. 188,378
Patented July 12, 1960

188,378

COMPUTER CONSOLE

Walter F. Kraus and James J. La Due, Poughkeepsie, N.Y., assignors to International Business Machines Corporation, New York, N.Y., a corporation of New York

Filed June 12, 1959, Ser. No. 56,322

Term of patent 14 years

(Cl. D26—5)

FIG. 1

Des. 188,378

PAGE 2

FIG. 2

FIG. 3

Figure 1 is a front perspective view of a computer console showing our design.

Figure 2 is a rear perspective view of the same.

Figure 3 is a side elevation of the same.

The other side of the computer is the same.

We claim:

The ornamental design for a computer console, as shown and described.
